CLOTHES WRINGER

Filed Feb. 19, 1921

2 Sheets-Sheet 2

UNITED STATES PATENT OFFICE.

FREDERICK GEORGE SCHRANZ, OF PHILADELPHIA, PENNSYLVANIA, ASSIGNOR TO SOUTHWARK FOUNDRY & MACHINE COMPANY, OF PHILADELPHIA, PENNSYLVANIA, A CORPORATION OF PENNSYLVANIA.

CLOTHES WRINGER.

Application filed February 19, 1921. Serial No. 446,226.

To all whom it may concern:

Be it known that I, FREDERICK GEORGE SCHRANZ, a citizen of the United States, and a resident of Philadelphia, Pennsylvania, have invented certain new and useful Improvements in Clothes Wringers, of which the following is a specification.

My invention relates to clothes-wringers, and one object of my invention is to provide a wringer frame with improved pressure-applying means for the squeeze-rolls.

A further object of my invention is to provide a wringer frame made wholly of metal with improved pressure-applying means for the squeeze-rolls.

A further object of my invention is to provide a clothes-wringer, which may have a frame made wholly of metal, with quick-acting release mechanism for the pressure-applying means for the squeeze-rolls.

And a still further object of my invention is to provide an improved form of pressure-applying means for use with the bearings, which may be of wood, employed with the spindles of the squeeze-rolls; the upper bearings, which overlie the spindle of the upper squeeze-roll, being provided with a simple form of wear-member to take the thrust and wear occasioned by the pressure-applying means which are directly associated with the quick-release device.

These and other features of my invention, are more fully described hereinafter, reference being had to the accompanying drawings, in which:

Figure 1, is a front elevation, partly in section of a clothes-wringer having my improved pressure-applying means for the squeeze-rolls and one form of quick-release device therefor, within the scope of my invention.

Fig. 2 is a sectional view on the line II—II, Fig. 1.

Fig. 3, is a sectional view on the line III—III, Fig. 1.

Fig. 4, is a view, similar to Fig. 1, illustrating another form of quick-release device for my improved pressure-applying means, within the scope of my invention.

Fig. 5, is a sectional view on the line V—V, Fig. 4.

Fig. 6, is a sectional view on the line VI—VI, Fig. 4, and

Figs. 7 and 8, are views illustrating details of my invention.

The improved wringer frame to which the features constituting my present invention have been applied may be of metal, substantially U-shaped, in contour, and may comprise upright hollow end portions with a lower connecting cross-bar; such frame being formed in one or a plurality of sections. In the drawing I have illustrated a frame made of a plurality of sections, 1 and 2, fitting together on a median or substantially median line, as clearly illustrated in Fig. 2, and secured in place by suitable means; such for instance, as the rivets 3. Such frame may be identical with that shown and described in my pending application, filed Sept. 24, 1920, Ser. No. 412,449.

The sections 1 and 2 are provided with upright end portions 1^a and 1^b, and 2^a and 2^b, and these end portions may be provided with inwardly disposed flanges or ribs 4, providing channels adapted to receive bearing blocks 5, for the spindles 6, or squeeze rolls 7; said bearing blocks having side ribs 5^a fitting the channels provided by the flanges 4. These bearings are preferably of hard wood, and may be cut from a previously formed blank in the manner described in my application before referred to. The bearing blocks are applied to the upper side of the spindle of the upper roll and the lower side of the spindle of the lower roll, and the lower bearings may be supported by inwardly disposed lateral projections 8 carried by the end posts or standards of the frame.

At one side of the wringer frame I provide a housing 9, which may be integral with the parts 1^b and 2^b making up one of the hollow end portions, which housing receives the gears 10 and 11, carried by the spindles 6, of the squeeze-rolls 7. When the frame is made in a plurality of sections, such housing may be formed one half on each upright end portion 1^b and 2^b of the sections making up the frame.

Hinged at 12 to the upright end portions 1^a and 1^b of the section 1, are caps 13 and

14, which overlie the top of these end portions, as clearly illustrated in the drawings, and these cap members carry at their opposite ends bolts 15, hung from pivot pins 15^a, 5 mounted in pairs of ears 13^a and 14^a of the cap members 13 and 14; said bolts being adapted to underlie pairs of lugs 16, carried by the upright end portions 2^a and 2^b of the section 2. The bolts 15 carry springs 10 17 interposed between washers 18 and 18^a also carried by the bolts and which may be cupped to receive the ends of the springs; the washers 18 directly underlying the respective pairs of lugs 16. The bolts 15 may 15 be provided with suitable nuts 19 engaging the washers 18^a whereby the tension of the springs 17 may be adjusted to an extent to hold the parts securely in position and apply the desired pressure to the squeeze- 20 rolls. The cap 14 is provided with an extension 14^b, preferably integral therewith, to overlie the gear housing 9.

In the present instance, the wringer structure is provided with an improved form 25 of pressure-applying device for the squeeze-rolls 7, comprising lugs or projections 20 and 21 disposed on the under sides of the cap members 13 and 14 respectively, and preferably integral therewith, which lugs or 30 projections directly engage wear pieces 22, in the form of metal yokes, carried by the bearing blocks 5, for the spindle of the upper squeeze roll; the leg portions of which yoke members lie in grooves 5^b formed in 35 the side portions of said bearing blocks, and nominally engage the side walls of the upright end portions.

In this arrangement of my improved quick-release mechanism, the bolts 15 have 40 upwardly extending members or projections 23 disposed at an angle with respect to said bolts so as to extend over the squeeze rolls, and the upper ends of said members 23, are connected at 24, to a cross-bar 25, which 45 forms an operating handle. The members 23 may be integral with the bolts 15 or rigidly secured thereto. By depressing said handle 25, the bolts 15 may be swung on their pivot pins 15^a, and release the springs 50 17 from engagement with the pairs of the lugs 16. To completely release this pressure-applying device it is only necessary to depress the handle 25 to the position shown by dotted lines in Fig. 2, whereupon the 55 spring bolts 15 and the caps 13 and 14 will be withdrawn from their operative engagement with the lugs 16 and all danger of the fingers of the operator being injured if caught between the squeeze rolls is avoided; the upper roll being completely freed from 60 the pressure applied by the spring 17. In like manner, the rolls may be released if the garments passing through the squeeze-rolls tend to catch upon the same and wind 65 thereon.

In the structure illustrated in Figs. 4, 5, et seq., the frame of the wringer is of the same type as that illustrated in Figs. 1 and 2, and the same form of cap members 13 and 14, having the lugs or projections 20 and 21 respectively, on their under side, for engagement with the yoke members carried by the bearing blocks for the spindle of the upper squeeze-roll, are employed. Instead of mounting these bolts on independent 70 pivot pins, however, I provide a cross-bar 30, journaled in the pairs of ears 13^a and 14^a of said cap members; said cross-bar being squared or otherwise shaped at 31 to have a position connection with said bolts 15, so that any rotative movement applied to said cross-bar will tend to move the bolts 80 from their engagement with the pairs of lugs 16 of the end portion 2^a and 2^b, of the sections 2. 85

For the purpose of actuating the cross-bar 30, it may be provided with a laterally disposed arm or handle 33, which may be disposed at a right angle to the cross-bar, and extend above the same. It will be understood, therefore, that when this handle 33 is depressed to a sufficient extent, that indicated by dotted lines in Fig. 6, for instance, it will disengage the bolts 15 from the pairs of lugs 16, thereby releasing the 90 springs 17 applying pressure to the rolls and avoiding all danger of the fingers of the operator becoming pinched between the same. In like manner, the rolls may be released if the garments passing through the 95 squeeze rolls tend to catch upon the same and wind thereon. 100

As in the structure of my pending application before referred to, a drain board 35, 105 also of metal may be arranged to lie below housings 36, formed on the inside of the upright end portions of the frame for the outer ends of the squeeze-rolls in each form of structure, and this drain board may be adjustably held in place in the same manner 110 as illustrated in my pending application. The usual guide plates 37, to direct the garments to the bite of the squeeze-rolls may be employed, as in all similar structures, said guide plates having projections 38 which engage the edges of the 115 housings 36.

Power to drive the squeeze rolls may be applied to either spindle but in the present case I have shown the lower spindle as projecting beyond the end of the frame as indicated at 6^a, for operative engagement with a driving element; the shaft of a suitably actuated motor for instance. In lieu 120 of this, the projecting spindle may be engaged by a suitable crank handle, or other form of power-applying member.

As in the structure of my pending application, it will be readily understood that as soon as the cap members 13 and 14 are re- 125 130

leased from engagement with the wear members 22, the squeeze rolls 7 with the bearing blocks 5 may be removed. This permits ready assembly and removal of the various parts of the structure, for renewing the bearings or squeeze-rolls or other repairs, as occasion may require. There are no parts to get out of order or readily break, and any suitable form of clamping device 10 may be employed to attach my improved wringer to a washing machine, or tub, or at any other desired point.

It will be understood that I do not wish to be limited to the exact construction disclosed in the drawings and described herein, and my claims are designed to cover any equivalent construction having the same or a similar object in view. It will also be understood that my improvements may be 20 applied to wooden or metal frames, and that the latter may be made of cast or pressed metal, without departing from my invention.

I claim:

25 1. In a clothes wringer, the combination of a frame having hollow upright end portions, removable bearing blocks fitting within said hollow end portions, squeeze-rolls having spindles in engagement with said bearing blocks, cap members hinged to said end portions and overlying the same, bolts hinged to said cap members, and tension means for releasably holding the latter in operative engagement with the end portions 30 when the cap members are in position; said cap members operatively engaging the bearing blocks for the upper squeeze-roll and serving to transmit thereto the pressure exerted by said tension means.

40 2. In a clothes wringer, the combination of a frame having hollow upright end portions, removable bearing blocks fitting within said hollow end portions, squeeze rolls having spindles in engagement with said bearing blocks, cap members hinged to said end portions and overlying the same, bolts hinged to said cap members, springs carried by said bolts and releasably holding the latter in operative engagement with the end portions 45 when the cap members are in position; said cap members operatively engaging the bearing blocks for the upper squeeze roll and serving to transmit thereto the pressure exerted by said springs, and 50 means for simultaneously releasing said spring bolts and the cap members connected thereto whereby the pressure exerted to keep the squeeze-rolls in operative engagement may be relieved.

55 3. In a clothes wringer, the combination of a frame having upright end portions, removable bearing blocks fitting within said end portions, a pair of squeeze rolls mounted in said frame and having spindles engaging 60 said bearing blocks; the spindles of the up-

per roll underlying its bearing block, cap members hinged to the top of said end portions, a bolt pivotally connected to each of said cap members opposite its hinged connection with the frame, releasable tension 70 means for each bolt serving to hold the latter in operative engagement with said end portions when the cap members are in position, and rounded lugs carried by the underside of the cap members and integral therewith for engaging the bearing blocks for the upper squeeze roll, said lugs serving to transmit to said upper bearing blocks and the upper roll the pressure exerted by said tension means. 75

80 4. In a clothes wringer, the combination of a metal frame, squeeze-rolls mounted in said frame; said squeeze rolls having projecting spindles, bearing blocks for the under side of the lower spindle and the upper side of the upper spindle, cap members hinged to said frame, bolts hinged to said cap members, springs carried by said bolts and releasably holding the latter in operative engagement with the frame when said cap members are in position; said cap members operatively engaging the bearing blocks for the spindle of the upper squeeze roll and serving to transmit thereto the pressure exerted by said springs, and a movable handle connecting said bolts; said handle constituting means whereby said bolts may be simultaneously released from the frame to instantly relieve the pressure exerted by the springs upon the squeeze rolls. 90

95 5. In a clothes-wringer, the combination of a frame, bearing blocks mounted in said frame, squeeze-rolls mounted in said frame and having spindles in engagement with said bearing blocks, cap members hinged to said frame and lying in operative engagement with the upper bearing blocks, bolts pivotally connected to said cap members, springs for releasably holding the bolts to the frame and applying pressure to said squeeze-rolls, extensions carried by said bolts and projecting upwardly from their pivotal connection, and a handle connecting said extensions; said handle constituting means whereby the bolts can be instantly and simultaneously released to relieve the pressure of said springs from the upper squeeze-roller. 105

110 6. In a clothes-wringer, the combination of a frame having hollow upright end portions, bearing blocks fitting within said end portions, squeeze-rolls mounted in said frame and having spindles in engagement with said bearing blocks, cap members hinged to the top of said end portions, lugs carried by said cap members in operative engagement with the upper bearing blocks, bolts pivotally connected to said cap members opposite their hinged connections, 115 springs for releasably holding the bolts to 120

125 130

the upright end portions and applying pressure to said squeeze-rolls, extensions carried by said bolts and projecting upwardly from their pivotal connection, and a handle extending longitudinally of the wringer-frame and connecting said extensions; said handle constituting means whereby the bolts can

be instantly and simultaneously released to relieve the pressure of said springs from the upper squeeze-roll.

10

In witness whereof I have signed this specification.

FREDERICK GEORGE SCHRANZ.
